AUTOMATIC SWITCH

Reginald Taylor, Liverpool, England, and George Thomas Baker, Caerphilly, Wales, assignors to Associated Telephone and Telegraph Company, Chicago, Ill., a corporation of Delaware

Application October 12, 1935, Serial No. 44,768
In Great Britain November 3, 1934

16 Claims. (Cl. 179—18)

The present invention relates to telephone systems and automatic switches for use therein and is more particularly concerned with improved testing arrangements for hunting switches of the type which hunt for battery potential characterizing idle switches or other pieces of apparatus. The chief object of the invention is to provide simplified circuits giving better facilities for the transmission of booster battery metering pulses over the test conductor and ensuring that a contact to which booster battery is connected shall not test idle to a switch hunting thereover.

According to one feature of the invention in an automatic hunting switch having a free line indicated by the presence of battery potential of one polarity on the test contacts to which contacts booster battery potential of the opposite polarity is also adapted to be applied while the associated line is in use, a rectifier is provided in circuit with the testing means so as to distinguish between the various potentials on the test contacts and only in the event of a free line being encountered to arrest the switch and bring about the establishment of a through connection which connection is adapted to be maintained as long as either booster battery or earth potential is applied to the test lead.

Other features relate to improved arrangements for giving preference to one particular set of wipers of a large capacity switch if both encounter idle lines simultaneously and to arrangements for reducing the number of relays required by the use of a combined test and changeover relay.

The invention will be better understood from the following description of one method of carrying it into effect, reference being had to the accompanying drawings comprising Figs. 1 and 2 which show a group selector provided with two sets of wipers and adapted to test two groups of outlets simultaneously.

The switch is of the two-directional type having so-called rectangular movement in which no release magnet is provided but the restoration of the switch to normal is effected by stepping the switch wipers forward to the end of the level and then allowing them to complete their restoration by a vertical and rotary movement. A switch of this type is described in the patent of Robert N. 50 Saxby, No. 2,028,689, filed September 22nd, 1932. An increase in the hunting speed is achieved by allowing the magnet to operate in a self-interrupted circuit.

When the switch is taken into use a circuit is completed between the negative and positive conductors over which relay A operates and completes a circuit for relay B. If the switch is functioning as a first selector, earth to the lower winding of relay A may be supplied by way of a 55 dial tone transformer, as indicated by the dotted

earth connection, to inform the calling subscriber that the circuit is ready to respond to the dialled impulses. Relay B operates and at armature *b1* replaces battery fed via resistance YA to the P wire with earth to guard the circuit, and at armature *b3* lights the individual supervisory lamp LP in circuit with the common conductor 10 extending to exchange alarm equipment which provides a signal in case the switch is seized and not operated within a predetermined time. 10

Upon the reception of the setting impulses, relay A responds and repeats them by way of armature *a1* to the vertical magnet VM in series with the low resistance left-hand winding of relay HX and accordingly the wipers are raised to the desired level. Relay HX operates in this circuit and at armature *hx1* short-circuits its right-hand winding thereby producing a slugging effect which is sufficient to hold the relay operated continuously during the impulsive period. Relay B 20 is similarly held by reason of the copper slug on its core. As soon as the wipers leave the normal position, off-normal springs *N1* and *N2* are operated mechanically but perform no immediate function. 25

At the end of the vertical impulsive, relay A holds and after a short interval relay HX releases, and at armature *hx2* completes a self-interrupted driving circuit to the rotary magnet RM to earth supplied over the common conductor 30 *11* extending to release alarm equipment and accordingly the wipers are rotated in search of a free outlet in the level selected. Normal rotary springs *NR1* and *NR2* are operated mechanically as soon as the wipers commence to rotate and complete a testing circuit for relay HX to the test wiper *P1*. The testing circuit for relay HY to the test wiper *P2* is already completed by armature *b4*. 35

Idle outlets are marked in the banks *P1* and *P2* 40 by the presence of resistance battery on the test contacts and if it is assumed that the wiper *P1* is the first to encounter a free outlet the fast operating test relay HX immediately operates over the following circuit, earth at armature *b1*, metal rectifier MRA, right-hand winding of relay HX, normal rotary springs *NR2*, left-hand winding of relay HX, armature *hx2*, armature *b2*, normal rotary springs *NR1*, wiper *P1* to resistance battery on the idle test contact. The presence of the 45 metal rectifier MRA in the circuit of relay HX ensures that the relay will not operate when the test wiper encounters a line on which booster battery metering is taking place as it offers a high resistance to current flow in the reverse direction which would otherwise occur when booster battery was encountered and would consequently cause the switch to extend the call to an existing connection. At its armature *hx2* relay HX opens the drive circuit for the rotary magnet and at 50 55 60

armature $hx1$ completes a temporary holding circuit over its left-hand winding which is sufficiently low in resistance to guard the outlet selected. Relay HX also at armature $hx2$ extends battery from the rotary magnet to the switching relay HA which operates and locks over its armature $ha1$, at armature $ha2$ opens the test circuit to relay HY and at armatures $ha4$, $ha5$ and $ha6$ extends the test lead and the negative and positive speaking leads over the upper set of wipers to the succeeding switch. Relays A , B and HX thereupon release, while the switching relay HA remains held to earth which is now fed back over the test lead from the succeeding switch.

15 If wiper $P2$ is the first to encounter a free outlet relays HY and HB operate with similar results to those already described except that the connection is extended to the succeeding switch over the lower set of wipers. The metal rectifier MRB has the same function in relation to relay HY that the metal rectifier MRA has in relation to relay HX . Further, at armature $hb1$ a circuit is prepared to the common conductor 12 extending to a test buzzer which may be operated by short-circuiting the test jack springs $T2$ to indicate which set of wipers is connected up without having to remove the dust cover and examine the actual relays.

30 If both test wipers $P1$ and $P2$ encounter idle outlets simultaneously both test relays HX and HY operate together, but it will be noticed that relay HX at armature $hx2$ immediately disconnects the operating battery from relay HB thus preventing this relay from operating. Relay HA therefore operates and the upper set of wipers always receives priority under these conditions.

35 It will be appreciated that as relays HX and HY are employed only as test relays and that separate switching relays HA and HB are provided, the former relays need only carry a few springs and may be designed to operate very quickly when an idle line is found. On the other hand, the switching relays HA and HB need not be quick to operate and may therefore be designed to have a greater margin in other directions, thus they may be adjusted with a heavy spring tension which causes them to release quickly.

40 It will also be noted that after the metal rectifiers have fulfilled their function of guarding against seizing a line on which booster battery is present they are disconnected and a straight-through connection is provided from the test wiper to the incoming test lead to permit the passage of booster battery metering impulses over the test lead.

45 If all outlets in the level selected prove busy, the wipers rotate to the 11th position where test relay HY operates in series with battery fed through resistance YA to open the driving circuit to the rotary magnet. Owing to the mechanical operation of cam springs in the 11th position, relay HB is prevented from switching since its circuit is opened at springs $S3$, while at springs $S2$ the low resistance holding circuit to relay HY is disconnected since this would otherwise tend to shunt the common resistance marking battery YA to such an extent as to prevent other selectors from switching through in the 11th position. Furthermore, at the make contacts of cam springs $S1$ busy flash and tone from the cam assembly BF is extended through the lower winding of relay A to the positive line to inform the calling subscriber that the connection is unavailable. During the flash period, relay A is released

but owing to the closure of cam springs $S2$ relay B is held over its right-hand winding to holding battery supplied from the cam assembly BH . Earth is also connected to wiper $P1$ by cam springs $S3$ to operate an overflow meter (not shown) connected to the 11th bank contact.

5 Upon the release of the connection at the end of the conversation relay HA or HB , as the case may be, releases whereupon the self-interrupted driving circuit is again completed to the rotary magnet RM from earth on the common conductor 11 extending to the alarm equipment, and accordingly the wipers are rotated clear of the banks after which they fall and restore backwards below the banks to their normal position. The off-normal springs $N2$ now release and open the homing circuit while battery is again connected to the test conductor via resistance YA to mark the switch as idle. Preferably during the vertical release movement of the wipers the rotary magnet is mechanically prevented from opening its interrupter contacts so that there is no tendency for it to chatter.

10 In case for any reason the switch fails to restore, the off-normal springs $N2$ remain closed and as the result of the continued connection of battery to conductor 11 the alarm equipment functions after a delay period and provides an indication of the faulty condition.

15 Terminals marked $T1$ to $T8$ in the drawings are assembled in the form of a test jack located at the front of the switch to facilitate testing.

20 The condenser QA and associated resistance is for the purpose of preventing arcing taking place at the interrupter contacts associated with the driving magnets.

25 We claim:

1. In an automatic switch arranged to be driven over outlets responsive to the closure of a driving circuit, a combined test and guard relay effective to test for idle-indicating potential on the test conductor of an idle outlet, contacts on said relay closed when the relay energizes over the test conductor of an idle outlet for closing a low-resistance guarding circuit through a winding of the relay to apply guarding potential to the test conductor of the outlet, a switching-through relay, and additional contacts on the combined test and guard relay for opening the driving circuit and for energizing the switching-through relay.

30 2. In a free-hunting automatic switch having a driving circuit, means for closing the driving circuit to cause the switch to hunt over a group of outlets, a first relay in the switch and means for energizing it over the test conductor of an idle outlet, a switching-through relay for switching through to the idle outlet, contacts operable by the first relay upon energization for applying a guarding potential to the test conductor of the outlet found to be idle, and other contacts operable by the said first relay upon the energization thereof to open the driving circuit and to operate the said switching-through relay.

35 3. In a free-hunting automatic switch where-in test conductors of outlets are tested successively during the hunting movement of the switch and wherein the hunting movement of the switch is terminated and a switching-through operation is performed when an idle outlet is found, a quick-acting test and guard relay and a switching relay, means for operating the quick-acting test and guard relay immediately over the test conductor of an idle outlet to place a guarding potential on the outlet and to terminate the driv- 75

ing movement, and means for subsequently operating the switching-through relay to extend connection to the outlet found to be idle.

4. In a two-motion automatic switch having a control relay, means in the switch for maintaining said control relay operated during the primary movement and for restoring it to start the secondary movement, outlets successively engaged during the secondary movement, and means for re-operating said control relay over the test conductor of an idle outlet to terminate the secondary movement.

5. In a two-motion automatic switch having a control relay and having groups of outlets, each outlet having a test conductor adapted to be engaged by a test wiper of the switch during the secondary movement, means in the switch for maintaining the control relay operated during the primary movement and for restoring it at the end of the primary movement to start the secondary movement, and means for re-energizing said relay over the test wiper of the switch and the test conductor of an idle outlet to terminate the secondary movement when an idle outlet is found.

6. In an automatic switch having alternative sets of wipers, each set of wipers having access to a different set of outlets, means for driving the wiper sets over their associated outlets, each wiper set including a test wiper adapted to cooperate with test contacts of the associated outlets, there being also a separate test relay for each wiper set and a separate switching-through relay, means effective when either wiper set engages an idle outlet for energizing the test relay of such wiper set over the associated test wiper and the test contact of the idle outlet, contacts on the test relay for operating the associated switching relay, and contacts on one test relay for opening the circuit of the switching relay associated with the other test wiper, whereby one set of wipers is given preference over the other in the event that both wiper sets encounter idle outlets at the same time.

7. In combination, an automatic hunting switch having access to a group of outlets and to an additional outlet used as an overflow outlet in case the other outlets are all engaged, each of the outlets having a test contact on which an idle-indicating potential is maintained while the outlet is idle, said switch having a test wiper and a combined test and guard relay, means for operating said relay over the test wiper and the test contact of an idle outlet to terminate the driving movement of the switch and to apply a guarding potential to the test contact, and additional means effective with the arrival of the selector on the said overflow outlet for preventing the application of guarding potential to the overflow outlet, whereby the overflow outlet is not marked engaged to the other switches having access to it.

8. An automatic hunting switch having a free line indicated by the presence of battery potential of one polarity on the test contacts to which contacts booster battery potential of the opposite polarity is also adapted to be applied while the associated line is in use in which a rectifier is provided in circuit with the testing means so as to distinguish between the various potentials on the test contacts and only in the event of a free line being encountered to arrest the switch and bring about the establishment of a through

connection which connection is adapted to be maintained as long as either booster battery or earth potential is applied to the test lead.

9. An automatic hunting switch including a test relay adapted to distinguish between normal battery potential and booster battery potential and a switching relay arranged to be operated responsive to the operation of said test relay and to remain operated independently thereof.

10. An automatic hunting switch including a test relay arranged to operate over a high resistance winding and a low resistance winding in series when an idle line is encountered and thereupon to shunt its high resistance winding to guard said line in which the switch includes also a switching relay for maintaining a straight-through connection from the incoming test lead to the test wiper throughout the connection.

11. An automatic hunting switch including a test relay arranged to operate over a high resistance winding and a low resistance winding in series when an idle line is encountered and thereupon to shunt its high resistance winding to guard said line in which said relay is also arranged to initiate the automatic hunting movement after the switch has responded to a series of impulses.

12. An automatic switch as claimed in claim 10 in which the test relay is provided with one armature for shunting its high resistance winding and with a second armature arranged to open the driving circuit and complete a circuit for the switching relay.

13. An automatic switch as claimed in claim 9 provided with two sets of wipers in which a separate test relay is associated with each set of wipers and is arranged to control a corresponding switching relay.

14. An automatic switch as claimed in claim 9 in which an overflow contact is provided at the end of a group of contacts and is marked with idle-indicating potential to cause the switch to select said contact when all the preceding contacts in the group are busy.

15. In an automatic switch, a test relay operated when the test wiper of said switch encounters a contact connected to one pole of battery, a switching relay, means controlled responsive to the operation of said test relay for operating said switching relay, and means controlled by said switching relay for providing a holding circuit therefor when the opposite pole of battery is connected to said contact.

16. In an automatic switch in which the wipers are directly controlled in a vertical direction to select a particular level of bank contacts and automatically rotated thereover to search for an idle trunk line, a test relay adapted to distinguish between exchange battery, ground, or booster battery potentials; a switching relay and an operating circuit therefor, said test relay operated only when the test wiper of said switch encounters exchange battery potential on an associated bank contact in a selected level to terminate the automatic rotation of the wipers and to complete the operating circuit for said switching relay, and means controlled responsive to the operation of said switching relay for maintaining said switching relay energized independently of said test relay.

REGINALD TAYLOR.
